UNITED STATES PATENT OFFICE.

LEO J. KELLY, OF HORNELL, NEW YORK.

ELECTRIC-IRON STAND.

Application filed June 9, 1927. Serial No. 197,709.

The object of the invention is to provide a stand for electric pressing irons and like implements in which is incorporated a controlling means for automatically opening the circuit on the iron or other device when resting upon the stand and when it has attained a predetermined temperature; to provide in a device of this kind regulating means so that the controlling means may be set or adjusted to operate at a particular temperature; to provide in a construction of this character a signalling means which will indicate the attainment of the desired temperature of the device placed on the stand; and to provide a construction which is equipped with both manual and automatic cut-outs in addition to the temperature cut-out.

With this object in view, the invention consists in a construction and combination of parts of which a preferred embodiment is illustrated in the accompanying drawings, wherein:

Figure 1 is a plan view of the invention.

Figure 2 is a longitudinal sectional view on the plane indicated by the line 2-2 of Figure 1.

Figure 3 is a plan view of the invention with the rest plate removed.

Figure 4 is a bottom plan view.

Figures 5 and 6 are transverse sectional views on the planes indicated by the lines 5-5 and 6-6 of Figures 1 and 3 respectively.

The rest plate 10 which receives the pressing iron or other similar device is supported on the transverse rollers 11, the latter being rotatably mounted in the side rails 12 of the frame which comprises a bed rail 14 on top of which is disposed a base plate 15, the latter carrying posts 16 by which the rails 12 are supported. The rails 12 follow the general outline of a pressing iron and the rest plate at the heel end is provided with a series of coils 17 which together with the rails define a continuous guard flange for the received iron.

A circuit closer and cut-out is carried by the frame below the rest plate and is serially included in circuit with the heating element of the iron, this circuit closer comprising a fixed contact 18 and cooperating movable contact 19, the latter being carried at the extremity of a lever 20 swingingly supported on a transverse stud carried by the spaced

standards 21 which are mounted at the nose 55 end of the base plate 15. The lever 20 consists of spaced elements between which is mounted a bell crank lever of which the arm 22 is disposed between the elements of the lever 20 and carries a transverse pin 23 60 spanning the elements of the lever 20 and disposed below the lower edges of the latter. The arm 24 of the bell crank lever which like the arm 22 is also a resistance arm, is provided for the actuation of the signalling means later described. The force arm of the lever is in the form of an abutment nose 25 disposed in a bifurcation 26 formed in the nose 27 of the rest plate. With the heel end of the rest plate 70 fixed, linear expansion of the plate due to the absorption of heat from the iron or other object resting thereon, will effect a pressure on the abutment nose 25 and the consequent elevation of the lever 20 through the medium of the resistance arm 22, the elevation of the lever 20 effecting separation of the contacts 19 and 18. The bell crank lever, like the lever 20, has a pivotal mounting, the two being concentric but the levers are independently movable.

The means for anchoring the heel end of the rest plate with reference to the base consists of tensile springs 28 terminally secured to a transverse bar 29, the latter being secured to and spanning standards 30 upstanding from the base, the springs being connected with the rest plate through a small yoke plate 31 with which is engaged a pin 32 depending from a tongue 33 constituting an integral rear extension from the rest plate. The bar 29 being fixed with reference to the base, the springs tend to draw the rest plate rearwardly, the movement in this direction being limited by the cooperating stops of which one consists of a screw 34 90 threadingly engaged with the bar 29 and the other a seat 35 carried by the tongue and engaging the terminal of the screw. The springs serve to keep the two stops in engagement and therefore fix the position of the heel end of the rest plate with reference to the base and the rest plate in expanding changes its position on the base or frame with reference to the nose end, the transverse rollers 11 providing for freedom of movement in expanding, despite the superposed weight in the form of the iron carried by the stand.

Obviously the adjustment of the screw 34 varies the position of the nose end of the rest plate with reference to the abutment nose 25 and therefore provides for the operation of the cut-out at different temperatures, depending on the setting of the screw 34, the adjusting means of which consists of a transverse rod 36 slidably mounted in the head of the screw. An indicator is provided so that the hit and miss method of adjustment of the screw 34 is avoided, the indicator consisting of a swinging pointer 37 pivotally mounted on the base plate and movable over a scale 38 and actuatable through a link 39 having a pin and slot connection 40 with it, the link being pivotally mounted, as indicated at 41, on the base plate and having a slot 42 in which the pin 32 engages. On the under face of the base plate 15, there is mounted a terminal block 43 from which a lead 44 extends, connected to the fixed contact 18 and from which a lead 45 also extends, the latter connecting with a block 46 of readily fusible material, which block has a pig tail connector 47 connecting it with the movable contact 19. The block 43 is designed for the reception of a conventional plug 48 connected in one side only of the supply circuit, a lead 49 running from this plug to the heating element of the iron and a lead 50 running from the plug to the main plug 51 from which a lead 52 runs to the heating element. Thus the circuit closer comprising the contacts 19 and 18 is in series of the heating element of the iron and when they are separated the circuit on the heating element is opened and correspondingly closed when they are in contact. The circuit closer is actuated by the rest plate and so is the signal which may be audible or visible but in the present embodiment is shown as an audible signal, the same comprising a gong 53 mounted on the base plate 15 in position to be engaged by the clapper 54 which is carried by the spring stem 55, the latter being pivotally mounted as indicated at 56 in a bracket 57 and spring impelled against a stop 58 which normally holds the clapper 54 spaced from the gong, the resiliency of the stem permitting the clapper to engage the gong, when the stem is swung in a direction away from the stop and suddenly released. The means for actuating the clapper consists of a tail extension 59 of the stem and a trip member 60 adjustably mounted on an arm 61, the trip being adjustable longitudinally of the arm by reason of the exterior threads 62 on the latter. The trip is provided with a guard plate 63 on that side which engages the tail extension 59. The arm 61 is slidably mounted in a guide bracket 64, passing slidably through a diagonal slot 65 formed in the latter, the arm also being pivotally con-

nected at the extremity remote from the trip with one end of a lever 66 which is pivotally mounted at the other end as indicated at 67, on the base plate and which has an operative connection with the arm 24 of the bell crank lever through a link 68. Upon movement of the bell crank lever, longitudinal movement is imparted to the arm 61, bringing the trip into engagement with the tail extension 59 of the clapper stem and the clapper is thus rocked away from the gong until the notch 69 in the arm is at the edge of the leaf 70 which is mounted on the bracket 64 beside the slot 65. The arm may at this time swing laterally due to the notch, leaving the tail extension 59 free, so that the clapper may swing back toward the gong. Thus, a quick release for the clapper is provided. The arm moving laterally, also moves upwardly due to the inclination of the slot 65, so that when the arm moves longitudinally in the other direction, as when the bell crank lever rocks in a reverse direction due to the cooling of the rest plate, the trip may drop in behind the tail extension preparatory to operating the clapper upon the rest plate again expanding. The pin 71 effecting the pivotal connection between the arm 61 and the lever 66 extends through a slot 72 in the base plate 15 and below the latter has connected with it a link 73, which link has a pivotal connection with an arm of a bell crank lever 74, the latter being pivotally mounted in brackets 75 spanning a slot 76 in the base plate. The remaining arm of the bell crank lever 74 carries a weight 77, the gravitational tendency of the weight tending to maintain the lever 66 and arm 61 in a position where the trip 60 is behind the tail extension 59 preparatory to engaging the latter. A mechanical cut-out is provided for the actuation of the circuit closer comprising the contacts 18 and 19 and this comprises a rock shaft 78 disposed transversely of and below the lever 20, the rock shaft having a lateral lug 79 which, when the rock shaft is in one position, engages the lever 20 and thus elevates the contact 19 out of engagement with the contact 18. The rock shaft is actuated through a hand lever 80 disposed at the heel end of the stand, this hand lever being carried at the upper end of a shaft 81 rotatably mounted in the base plate and carrying below the latter a crank 82 with which a link 83 is pivotally connected, the latter having a pivotal connection with a crank 84 and carried by the rock shaft 78 and extending through a slot 85 formed in the base plate. In the operation of the invention, the plug 48 is coupled with the block 43 and the plug 51 inserted in an outlet, the iron or other implement with which the leads 49 and 52 are connected being placed on the stand on the rest plate 10. As the implement heats,

its heat is transferred to the rest plate and the latter expands, engaging the abutment nose 25 and rocking the bell crank lever of which it is a part, effecting the separation 5 of the contacts 18 and 19 and the actuation of the signal in the manner before described. As long as the temperature of the implement remains at the desired point, the contacts 19 and 18 will be held separated, but 10 upon dissipation of the heat and the contraction of the rest plate, they will be again brought into engagement, when the circuit on the heating element of the implement will be re-established and the temperature will 15 be raised until the circuit is again opened by the expansion of the rest plate. The screw 34 provides the adjustment for setting to have the device operate at a desired temperature, while the hand lever 80 provides 20 a cut-out for the manual actuation of the circuit closer 19—18; so that it will not be necessary to disconnect either the plugs 48 or 51 or to operate an electrical switch controlling the outlet. 25 Should any of the parts fail of operation, excessive heat will fuse the block 46 and thus effect the opening of the circuit at this point. The invention provides against fire hazards in that it provides an automatic means 30 for the control of an iron or like device when not in use and when resting upon its proper support or stand.

The invention having been described, what is claimed as new and useful is:

1. A device for the purpose indicated comprising a frame, a rest plate mounted in the frame, anchoring means for the heel end of the rest plate, and a circuit closer disposed to be engaged and actuated by the rest plate at the nose end upon linear expansion of the plate, the anchoring means consisting of a screw carried by the frame and abutting the plate, and springs tensioned between the frame and the plate, whereby the position of the plate may be varied with respect to 45 the circuit closer.

2. A device for the purpose indicated comprising a frame, a rest plate mounted in the frame, anchoring means for the heel end of the rest plate, said anchoring means being 50 adjustable to vary its position relative to the frame, and a circuit closer operatively connected with the rest plate at the nose end and actuatable by the latter upon linear expansion of the plate, the anchoring means 55 consisting of a screw carried by the frame and abutting the plate, springs tensioned between the frame and the plate, and an indicator operatively connected with the screw. 60

In testimony whereof he affixes his signature.

LEO J. KELLY.
